DESIGN FOR A VISE

James J. Connors, Meriden, Conn., assignor to
The Charles Parker Company, Meriden, Conn.,
a corporation of Connecticut

Application September 14, 1939, Serial No. 87,225

Term of patent 14 years

To all whom it may concern:

Be it known that I, James J. Connors, a citizen of the United States, residing at Meriden, in the county of New Haven and State of Connecticut, have invented a new, original, and ornamental Design for a Vise, of which the following is a specification, reference being had to the accompanying drawing, forming part thereof.

Fig. 1 is a perspective view of a vise showing my new design;

Fig. 2 is a side view of the same; and

Fig. 3 is an underside view thereof.

I claim:

The ornamental design for a vise, substantially as shown.

JAMES J. CONNORS.
